EDGE BINDING STRIP FOR DESK TOPS

Joseph H. McCarthy, Youngstown, Ohio, and Herbert P. Zimmermann, Amityville, N.Y., assignors to The General Fireproofing Company, Youngstown, Ohio, a corporation of Ohio

Application October 10, 1957, Serial No. 48,038
Term of patent 14 years

(Cl. D54—2)

Fig. 1.

Fig. 2.

Fig. 1 is a top plan view of an edge binding strip for desk tops showing our new design; and

Fig. 2 is a perspective view of the strip shown in Fig. 1.

The dominant features of our design reside in the portions shown in full lines. The dotted lines connecting the break lines indicate indeterminate length.

We claim:

The ornamental design for edge binding strip for desk tops, as shown and described.
